[57] CLAIM

The ornamental design for a combined accessories cabinet and mirror unit primarily used by a beautician, substantially as shown and described.

DESCRIPTION

FIG. 1 is a front elevational view of a combined accessories cabinet and mirror unit, primarily used by a beautician showing my new design.

FIG. 2 is a right side elevational view thereof;

FIG. 3 is a top plan view thereof;

FIG. 4 is a left side elevational view thereof; and

FIG. 5 is a rear elevational view thereof.
